ELECTRIC FURNACE

Filed March 1, 1928.

Inventor:
Robert M. Cherry
by Charles E. Tullar
His Attorney.

UNITED STATES PATENT OFFICE

ROBERT M. CHERRY, OF SCHENECTADY, NEW YORK, ASSIGNOR TO GENERAL ELECTRIC COMPANY, A CORPORATION OF NEW YORK

ELECTRIC FURNACE

Application filed March 1, 1928. Serial No. 258,334.

My invention relates to electric furnaces, especially to resistance heating units for electric furnaces, and has for its object the provision of a heating unit which is rugged in construction, efficient in radiating heat, and which may be easily removed from the furnace structure.

For a better understanding of my invention reference may be had to the accompanying drawings in which Fig. 1 is a side elevation view of a furnace embodying my invention, and Fig. 2 is a sectional view taken on the line 2—2 of Fig. 1, looking in the direction of the arrows.

Referring to the drawing, in carrying out my invention in one form I provide a furnace structure comprising side and roof walls 11 defining an elongated heating chamber 12, the walls being provided with an outer metal casing 10. These walls are preferably formed by an inner wall 13 made of heat refractory electrically insulating bricks. The casing 10 is spaced from inner wall 13 and the space between the casing and inner wall is filled with a suitable powdered refractory heat insulating substance, such as a diatomaceous material. A heat refractory bottom is also provided. An opening 12' is provided in one end wall through which the charge may be inserted and removed, or if desired the charge 30 may be pushed through the heating chamber and removed through a suitable opening provided in the opposite end.

The furnace is heated by means of one or more electric heating units 15 mounted in the upper part of the heating chamber and also if desired by one or more heating units 16 in the bottom of the heating chamber. In the elongated furnace shown a plurality of heating units are provided in both the top and the bottom of the furnace. The units at the top are slidably mounted on suitable brackets so that they may be separately inserted and removed from the side of the furnace. As shown, the upper unit 15 adjacent the end of the furnace is mounted at one side on a bracket 14 secured to the furnace wall, the opposite side of the unit being supported on a bracket formed by a plate 17 which is secured to the lower side of a supporting bar

18 extending across the heating chamber and having its ends secured in the side walls as indicated in Fig. 2. This supporting bar 18 may be rigidly secured to the furnace walls or it may be mounted so that it may be readily removed and replaced. The bar 18 is made from a suitable heat refractory material, such as aluminum oxide. It is shown as supported at the center by means of a metallic rod 19 extending upward through the roof of the furnace. The rod 19 may, however, be dispensed with, or a greater number may be used, depending on the width of the furnace and the weight of the heating units. The plate 17 projects beyond the opposite side of the bar 18 and forms a supporting bracket for one side of the next adjacent heating unit, as indicated in the drawing. A plurality of supporting bars 18 may be provided depending upon the number of heating units to be supported. In the event that only a single heating unit is used, the supporting brackets for both sides may be secured directly to the furnace wall.

The heating units 16 in the bottom of the furnace are similar in construction to the upper heating units 15 but are mounted in inverted relation with respect thereto in compartments 20 in the bottom of the furnace. These compartments are separated by walls 21 which form supports for the abutting edges of hearth plates 23 extending over the lower heating units. The hearth plates are preferably made of a heat resisting metal, such as nickel chromium alloy, as are also various other metal parts in the interior of the furnace.

Since as stated above, all of the heating units are identical, a description of one unit will be sufficient. A plurality of L-shaped hanger blocks 24 made of a suitable electrically insulating heat refractory material, such as aluminum oxide, are arranged side by side and held together by tie rods 25 passing through apertures therein, and the elongated supporting bars thus formed are held in pairs in parallel spaced relation by a plurality of metallic cross bars 26 made of a suitable heat resisting metal. As shown, five cross bars 26 are provided for each pair of support-

ing bars, one being provided at each end and three intermediate the ends. The elongated supporting bars and the cross bars 26 held together by means of the tie rods 25 thus form 5 a grid shaped framework which may be readily placed upon or removed from the supporting brackets 14 and 17.

Each hanger block 24 is provided in one side with a triangular recess 27 formed with 10 one of its sides at one end surface of the block i. e., at one end of the "L" and with its apex toward the center of the block. A hole 28 passes transversely through each block 24 at the apex of the triangular recess 27. These 15 holes and recesses in the blocks are provided to receive metallic hook members 29 made of a suitable heat resisting metal, one hook member being secured to each block and each hook member having a transversely bent end which 20 is inserted in the hole 28, the shank of the hook lying in the recess 27. The hook members 29 are inserted in the recesses 27 and 28 in the blocks while the blocks are being assembled and it will be observed that each 25 hook member is free to swing in its slot 27 on the pivot formed by its transversely bent end lying in the hole 28. The hook members are prevented from working out of the holes 28 by the sides of the adjacent blocks 24.

30 The hook members secured to each framework form supports for a heating resistor 22 which preferably is formed, as shown, from a ribbon of suitable resistance heating material, such as a nickel chromium alloy, the ribbon being bent into a plurality of zig-zag, substantially parallel lengths or convolutions extending back and forth between the parallel refractory bars of each framework. In the upper heating units, for example, it will 35 be observed that the bends joining the convolutions pass around the shanks of the hook members and lie in the hooks in the lower ends thereof. That is, a hook is provided at each bend of the resistor whereby the resistor 40 is supported. The recesses 27 and holes 28 in the blocks 24 are so placed in the blocks that the hook members are free to swing in a transverse direction with respect to the supporting bars formed by the blocks whereby the hook 45 members are free to swing in the direction of the expansion and contraction of the resistor due to changes in temperature.

It will be observed that the bottom heating units 16 are placed in inverted relation with 50 respect to the upper heating units 15, the resistor 22 in this case resting upon the insulating supporting bars formed by the blocks 24 instead of being hung on the hooks 29. The resistor is positioned laterally and held in 55 place by the hooks which are short enough so that the resistor cannot work under them.

At one end of each row of blocks 24 is placed one or more L-shaped blocks 30 made of the same material as the blocks 24, which 60 serve to close the recess 27 in the adjacent

block 24. These spacer blocks 30 may also be placed between the hanger blocks 24 at different points in order to lengthen the unit and adapt a certain resistor to different sized furnaces. Attached to and projecting from 70 some of the cross bars 26 are spacing insulators 31, which are rigidly attached to the cross bars 26 centrally thereof and extend between the pair of lengthis or convolutions of the resistor at this point. Attached to the cross bars 26 centrally thereof are insulating plates 32 containing slots 33, these plates extending in the opposite direction from the insulator 31. The return leads of the resistors 22 are brought through these slots 33 in the insulating plates 32 to one side or the other of the furnace where they are brought through the walls in proper insulating bushings, not shown. The other leads 34 of the resistors 22 are shown in Fig. 2 as passing 80 through suitable insulating bushings 35 in the furnace wall.

In Fig. 2 the right-hand side wall of the furnace is shown as containing removable sections 36 and the outer sheet metal casing 10 as containing removable plates 37. By removing the plates 37 and the sections 36 from the furnace wall an entire unit may be easily removed from the side of the furnace and repaired or replaced. In some instances it may be desirable to make the sections 36 integral with the frame structure of the units 15 or 16 so that a unit and a section of the furnace wall may be removed or replaced in one piece. Suitable tile members 38 are built 100 in the furnace wall to act as a support for the wall when the sections 36 are removed.

Several modifications may be made without departing from the scope of my invention. For instance, ledges 14 and 19 of the supporting brackets may each be provided with an upward flange, and a downward flange may also be provided on each of the refractory bars formed by the hanger blocks 24 so that by this flange fitting over the flange on the 105 cooperating supporting bracket the blocks will be held more securely on the supporting brackets 14 and 17, but will still be easily removable therefrom. Also, return leads of the resistors may pass through bushings at the 110 back side of the furnace and thus the insulating plates 32 might be dispensed with. On the other hand, the return leads of the bottom units 16 may be brought out along the side of the units through the proper insulators. It is to be observed that with my arrangement 115 the heating resistors 22 are so arranged that they are free to radiate heat to the work.

What I claim as new and desire to secure by Letters Patent of the United States is:

1. In an electric furnace a plurality of heating resistors, a grid shaped frame for each resistor, the grid frames of a number of said resistors serving to support their resistors directly above the bottom of the furnace 130

- and in horizontal relation therewith, and means for removably suspending a number of the grid frames from the upper walls of said furnace so as to support their resistors in horizontal relation with the resistors positioned in the bottom of said furnace, said suspending means comprising a supporting bracket extending across said furnace for supporting the adjacent edges of each pair of 5 said grid shaped frames.
- 10 2. In an electric furnace, a heating unit comprising a plurality of refractory L-shaped hanger blocks, means for supporting said blocks in parallel rows, a metallic member loosely mounted in and projecting from one leg of each L-shaped block, a heating resistor supported by said metallic members, and means attached to the walls of said furnace on which the other legs of said L-shaped blocks are adapted to rest.
- 15 3. In a heating unit for electric furnaces, a plurality of refractory hanger blocks, a grid shaped framework for holding said blocks in two parallel rows, a metallic hook member loosely mounted in and projecting 20 from each hanger block, and a resistance element supported by said hook members.
4. In a removable heating unit for electric furnaces, a plurality of refractory hanger blocks, a skeleton framework for supporting said blocks in parallel rows, a metallic member projecting from each of said blocks and pivotally mounted therein, and a sinuous resistance element supported by said metallic 25 members.
5. In a removable heating unit for electric furnaces, a plurality of refractory hanger blocks, a framework including a plurality of cross bars for supporting said blocks in parallel rows, metallic members loosely mounted in 30 and projecting from said blocks, a sinuous heating resistor supported by said metallic members, and insulating guide blocks attached to said cross bars and through which 35 pass the terminals of said resistor.
- 40 6. In a removable heating unit for electric furnaces, a plurality of refractory hanger blocks, a framework including a plurality of cross bars for supporting said blocks in parallel rows, metallic members loosely mounted in and projecting from said blocks, a sinuous heating resistor supported by said metallic members, insulating guide blocks attached to some of said cross bars and through which 45 pass the terminals of said resistor, and refractory spacing members attached to said cross bars and holding the turns of said sinuous resistor spaced from each other.
7. In a removable heating unit for electric 50 furnaces, a plurality of refractory blocks, means for securing said blocks together to form a pair of elongated refractory bars, metallic members connecting said refractory bars to form a supporting framework, metallic 55 hooks loosely secured to said bars, and a
- sinuous resistor shaped into substantially parallel length extending between said bars, said resistor being supported on said hooks at the junctions of said lengths.
8. In a furnace, an electrical heating resistor, a removable framework extending across said furnace, and metallic hook members secured to said framework engaging and supporting said resistor. 70
9. In an electric furnace, a heating unit comprising a plurality of refractory L-shaped hanger blocks, a grid shaped framework for holding said blocks in parallel rows, metallic hook members mounted in and projecting from each leg of each L-shaped block, a heating resistor supported by said metallic members and means attached to the walls of said furnace on which the other legs of said L-shaped blocks are adapted to rest. 75
10. In a heating unit for electric furnaces, a plurality of elongated refractory members, means for securing said members together to form a supporting framework, a plurality of metallic hook members pivotally secured to said refractory members and a heating resistor supported by said hook members. 80
11. A heating unit for electric furnaces comprising a plurality of refractory members, means for securing said refractory members together, a plurality of hook members pivotally secured to said refractory members and a heating resistor secured to said hook members. 85
12. A removable heating unit for electric furnaces comprising a plurality of elongated refractory members, means for securing said members together to form a supporting framework, a plurality of metallic hook members having transverse end supporting portions secured to said refractory members so as to be pivotally movable on said transverse end portions and a heating resistor supported by said hook members, said resistor extending back and forth between said refractory members. 100
13. In a furnace, a framework extending across said furnace and slidably removable from a side wall of said furnace, metallic hook members pivotally secured to said framework, and a heating resistor supported by said hook members extending back and forth between said hook members. 105
- In witness whereof, I have hereunto set my hand this 29th day of February, 1928.
- ROBERT M. CHERRY. 110
